U.S. Patent Application No. 09/143,448, filed Aug. 28, 1998, entitled "Hanging Data Binder."

Primary Examiner—Martie K. Holtje
Attorney, Agent, or Firm—Pennie & Edmonds LLP

[57] **CLAIM**

The ornamental design for an end portion of a hanging data binder, as shown and described.

DESCRIPTION

FIG. 1 is a perspective of an end portion of a hanging data binder showing our new design;
 FIG. 2 is a front view thereof;
 FIG. 3 is a rear view thereof;
 FIG. 4 is a top view thereof;
 FIG. 5 is a bottom view thereof;
 FIG. 6 is an end view thereof, the other end view being the same;
 FIG. 7 is a front view thereof in a first extended position;
 FIG. 8 is a rear view thereof;
 FIG. 9 is a top view thereof;
 FIG. 10 is a bottom view thereof;
 FIG. 11 is a front view thereof in a further extended position;
 FIG. 12 is a rear view thereof;
 FIG. 13 is a top view thereof;
 FIG. 14 is a bottom view thereof; and,
 FIG. 15 is a perspective view thereof in an environment. The hanging data binder structure depicted by means of broken lines in FIG. 15 has been shown for illustrative purposes only and forms no part of the claimed design.
